Inventor:

John T. Story,
by Michael J. & W. O. Stark,
Attorneys.

UNITED STATES PATENT OFFICE.

JOHN T. STORY, OF BUFFALO, NEW YORK.

DESIGN FOR AN ENVELOPE.

SPECIFICATION forming part of Design No. 19,695, dated March 11, 1890.

Application filed December 26, 1889. Serial No. 335,089. Term of patent 7 years.

To all whom it may concern:

Be it known that I, JOHN T. STORY, of Buffalo, in the county of Erie and State of New York, have invented and produced a new and original Design for Ornamenting the Face of Envelopes, of which the following is a specification, reference being had to the accompanying drawing, forming part thereof.

The figure is a face view of an envelope or-
10 namented with my design.

The leading features of this design consist in the curvilinear outlines B B' of the folds and flaps of the back of an envelope upon the face A thereof. Above these curvilinear 15 lines and near the upper edge of the face there are small circles C, through which a band or ribbon is represented to pass, which ribbon appears knotted at G, and the flowing

ends H H illustrated as passing beneath a seal E, having scalloped outlines and a circle 20 within. On the right-hand side there is a circular seal F, falling within and intersecting one of the curvilinear lines B', said circle, as well as the circle within the seal, bearing characters of any desired design or configu- 25 ration to suit the fancy of the designer.

What I claim is—

The design for an envelope, substantially as herein described and shown.

Witness my hand in presence of two sub- 30 scribing witnesses.

JOHN T. STORY.

Attest:

MICHAEL J. STARK,
WM. O. STARK.
